GESELLSCHAFT, OF ESSEN-ON-THE-RUHR, GERMANY.

MECHANICAL TIME-FUSE.

1,077,107.

Specification of Letters Patent.

Patented Oct. 28, 1913.

Application filed May 1, 1913. Serial No. 764,950.

To all whom it may concern:

Be it known that I, HEINRICH THIEL, residing at Ruhla, Germany, a subject of the Emperor of Germany, have invented a certain new and useful Improvement in Mechanical Time-Fuses, of which the following is a specification.

This invention relates to mechanical time fuses with clockwork, the setting of which is performed by the rotation of an external annular setting member surrounding the clockwork. In known fuses of this kind the external setting member has to be connected, by the aid of a clutch, which releases itself automatically when the shot is fired, to an internal setting disk which controls the moment of release of the ignition apparatus and which in the transport state of the fuse can be rotated on one of the shafts of the clockwork, independently thereof. In addition to this it is necessary in these fuses to have an apparatus which enables the setting disk to be automatically locked relatively to the shaft when the shot is fired.

Fuses which possess the advantage of rendering both the automatically releasable clutch and the locking device superfluous, are already known. The disadvantage of these fuses is however, that they cannot be set with the aid of fuse setting machines of the usual construction, for the reason that in their case the external setting member must not be rotated through an angle of 360° and more, as otherwise ignition would take place even while the fuse was being set.

The object of this invention is therefore, first and foremost to provide a fuse of the kind hereinbefore mentioned which possesses the advantage of the last mentioned fuses without being subject to their disadvantages. The invention also insures the advantage that the transport safety mechanism for the clockwork, can be considerably simplified.

A constructional example of the subject matter of the invention is illustrated in the accompanying drawing, in which—

Figure 1 is an axial section through a double fuse with a mechanical time fuse

constructed according to this invention and provided with clockwork and the adjacent portion of the projectile. Fig. 2 is a section on the line 2—2 of Fig. 1 looking from above, and Fig. 3 is a section on the line 3—3 of Fig. 2 looking from the left.

The driving spring A of the clockwork is mounted in a recess in a plate B¹ rigidly connected to the body B of the fuse, and one end of it is attached to the hollow main spindle C of the clockwork. The spindle C is connected to the escapement wheel E by a train of pinions D, D¹, D², D³. The corresponding balance F is mounted coaxially with the axis of the projectile. By means of a sleeve g¹ fixed to an arm G which sleeve projects into the hollow space in the spindle C, the said arm G is connected to the hollow main spindle C, so as to be capable of sliding thereon in the axial direction but incapable of rotation independent thereof. A spring g² placed in the sleeve g¹ tends to thrust the arm G in an axial direction. In the transport state of the fuse, the arm G is prevented from moving axially by a pawl H which is pivotally mounted on a plate B² and engages by means of an inclined projection h¹ over the arm G, in such a manner (see Figs. 2, 3) that the said catch H is compelled to turn in the direction of the arrow x (see Fig. 3) in order to release the arm G. This arm G being connected with the sleeve C, is under the action of the driving spring A, which tends to rotate it in the direction of the arrow y (see Fig. 2), against the pawl H. When the driving spring A is wound up, the pressure of the spring is so strong that the pawl H can only effect the releasing movement under the influence of the forces of inertia, which are set up when the shot is fired.

The arm G carries on its underside, and coaxial with the sleeve g¹, an annular shaped projection g³, against the inner peripheral surface of which, when the fuse is in the transport state, bears a projection or lug i¹ on a lever J which is rigidly connected to a spindle J² mounted to rotate in the frame of the clockwork. The arrangement of the parts is such that the lever J tends to fly

outward under the action of centrifugal force. To enable this movement to take place, the plate B^2 is formed with a slot b^3 running coaxially with the spindle J^2 and through which slot the projection i^1 on the lever J passes. Upon the spindle J^2 is arranged a shoulder i^3 . When the lever J with its projection i^1 bears against the inner peripheral surface of the annularly shaped projection g^3 , the said shoulder i^3 assumes such a position that a collar k^1 on the firing bolt K bears against the shoulder when the firing spring k^2 is cocked.

The fuse is set by means of a setting cap M which can be rotated relatively to the body B of the fuse. This setting cap has an annular portion m^1 , which lies just above the arm G when this latter is locked in the transport position by the pawl H h^1 . In the periphery of the annular portion m^1 are provided two contiguous recesses m^2 , m^3 . By rotating the setting cap M the recesses m^2 , m^3 can be brought into any angular position relatively to the arm G . To prevent the adjustment imparted to the setting cap from being lost when the shot is fired, an arrangement is provided in the well known way, by which the cap M is immovably secured to the body B of the fuse by the action of the 30 discharge, when the gun is fired.

The percussion fuse N arranged in the body B of the fuse is of known construction. The action of the mechanical time fuse is as follows:—Under the action of the forces 35 of inertia which are set up when the gun is fired, the setting cap is immovably secured to the body B of the fuse in the position given to it when the fuse was set. At the same time the pawl H which secures the arm G overcomes the stress of the driving spring A and swings in the direction of the arrow x (see Fig. 3) into its inoperative position so that the arm G is released. The result of this is, that on the one hand the clockwork 40 is set in motion and on the other hand the arm G moves in an axial direction under the pressure of the spring g^2 until it bears against the face of the annular portion m^1 of the setting cap M . As soon as the arm G , 45 which is rotated by the clockwork in the direction of the arrow y (see Fig. 2) has arrived under the recess m^2 it enters this latter under the pressure of the spring g^2 . At the same time the annular projection g^3 on 50 the arm G slides off the projection i^1 on the lever J , so that this latter swings outward under the action of centrifugal force. This movement causes rotation of the spindle J^2 . At the same time the shoulder i^3 slides off 55 the collar k^1 of the firing bolt K , and the firing bolt penetrates the primer under the action of the spring k^2 . The time at which the perforation of the primer takes place is, as will be seen from what has been stated 60 above, dependent upon the adjustment 65

which has been imparted to the setting cap M before the firing of the shot. If the charge of the projectile is not to be ignited by the mechanical time fuse but by the percussion fuse N , the cap M is so set that the recess m^3 lies above the arm G . This is the dead position of the fuse. In this position the arm G being immediately released by the pawl H , enters the recess m^3 under the action of the spring g^2 and is thereby prevented from rotating. Owing to the small depth of the recess m^3 the axial movement of the arm G which takes place under the action of the spring g^2 is so short that the projection i^1 on the ratchet lever J is not 70 released by the annular projection g^3 on the arm G . The firing bolt K therefore remains safe. When the projectile strikes, the fuse N then acts in the well known way. As the safety device formed by the pawl H h^1 75 prevents any axial movement of the arm G , when the fuse is in the transport state, the setting cap M may be rotated without danger as far as may be desired. This fact also 80 enables the fuse to be set with the aid of 85 fuse setting machines of the usual type of 90 construction.

I claim:—

1. A mechanical time fuse with a clock work having a firing pin, a casing and a dome revoluble relative thereto for setting the clock work; a driving spring and a centrally located spindle actuated by said spring, a member coaxially mounted to rotate with said spindle and constructed to be 95 axially displaced relative thereto, a safety device coacting with said driving spring for normally arresting said member until released by said safety device upon the firing of the projectile, and means coöperating with 100 said dome for displacing said member in the axial direction, and other means actuated by said member for retaining the firing pin in cocked position.

2. A mechanical time fuse with a clock 110 work having a firing pin, a casing and a dome revoluble relative thereto for setting the clock work; a driving spring and a centrally located spindle actuated by said 115 spring, a member coaxially mounted to rotate with said spindle and constructed to be axially displaced relative thereto, a safety device coöperating with said driving spring for normally arresting said member, said safety device comprising a hook shaped lever 120 in engagement with said member, said lever actuated by inertia releasing said member upon the firing of the projectile, means coöperating with said dome for displacing said member in the axial direction, and other 125 means actuated by said member for retaining the firing pin in cocked position.

3. A mechanical time fuse with clock work having a firing pin, a casing and a dome revoluble relative thereto for setting 130

the clock work; a driving spring and a centrally located spindle actuated by said spring, a member mounted to rotate with said spindle and constructed to be axially displaced relative thereto, a safety device coöperating with said driving spring for normally arresting said member until released by said safety device upon the firing of the projectile, and means coöperating with said dome for displacing said member in the axial direction, other means actuated by said member for retaining the firing pin in cocked position, said means comprising a spring adapted to push said member in an axial direction, an annular flange in said dome permitting slight axial displacement of said member, and a recess in said flange adapted to permit additional displacement of said member, whereby said member releases said other means.

4. A mechanical time fuse with a clock work having a firing pin, a casing and a dome revoluble relative thereto for setting the clock work; a driving spring and a centrally located spindle actuated by said spring, a member coaxially mounted to rotate with said spindle and constructed to be axially displaced relative thereto, a safety device coacting with said driving spring for normally arresting said member until released by said safety device upon the firing of the projectile, and means coöperating with said dome for displacing said member in the axial direction, other means actuated by said member for retaining the firing pin in cocked position, said other means comprising an annular collar on said member, a revoluble bolt having an arm in engagement with said collar, a radial finger on said bolt and an annular projection on said firing pin normally in engagement with said finger; whereby, on the axial displacement of said member, releasing said arm, said bolt actuated by centrifugal force will revolve, thereby releasing the annular projection and the firing pin.

5. A mechanical time fuse with a clock work having a firing pin, a casing and a dome revoluble relative thereto for setting the clock work; a driving spring and a centrally located spindle actuated by said spring, a member coaxially mounted to rotate with said spindle and constructed to be axially displaced relative thereto, a safety device coöperating with said driving spring for normally arresting said member, said safety device comprising a hook shaped lever in engagement with said member, said lever actuated by inertia releasing said member upon the firing of the projectile, means coöperating with said dome for displacing said member in the axial direction, and other means actuated by said member for retaining the firing pin in cocked position, said means comprising a spring adapted to push

said member in axial direction, an annular flange in said dome permitting slight axial displacement of said member, and a recess in said flange adapted to permit additional displacement of said member, whereby said member releases said other means, said other means comprising an annular collar on said member, a revoluble bolt having an arm in engagement with said collar, a radial finger on said bolt and an annular projection on said firing pin normally in engagement with said finger; whereby on the axial displacement of said member releasing said arm said bolt, actuated by centrifugal force, will revolve thereby releasing the annular projection on the firing pin.

6. A combination time and percussion fuse with a clock work having a firing pin governed by said clock work, a casing and a dome revoluble relative thereto for setting the clock work; a driving spring and a centrally located spindle actuated by said spring, a member axially mounted to rotate with said spindle and constructed to be axially displaced relative thereto, a safety device coöperating with said driving spring for normally arresting said member, said safety device comprising a hook shaped lever in engagement with said member, said lever actuated by inertia releasing said member upon the firing of the projectile, and means coöperating with said dome for displacing said member in the axial direction, said member comprising a spring adapted to push said member in axial direction, an annular flange in said dome permitting slight axial displacement of said member, a shallow notch and a deep notch in said flange adapted to permit additional displacement of said member, whereby said member releases said other means when engaging said deep notch, but still retains said other means and said firing pin in locked position, when said member engages with said shallow notch, thereby preventing the action of the time fuse.

7. A mechanical time fuse having a casing, a primer in said casing, a firing pin for igniting said primer, a spindle rotatably mounted on said casing, a clockwork for rotating said spindle, a revoluble annular setting member inclosing said clockwork for setting the fuse according to the desired distance of the bursting point, a locking member for retaining the firing pin in cocked position, said locking member being mounted on said spindle to rotate in unison therewith and adapted to be displaced relatively thereto for releasing said firing pin, and a safety device normally arresting said locking member against displacement until released upon the firing of the projectile; said setting member having a portion coöperating with said locking member during the turning of said spindle and being formed to permit the locking member to be dis-

placed relatively to the spindle for releasing said firing pin, when said spindle has reached a predetermined angular position, and means for causing such displacement.

5. 8. A mechanical time fuse having a casing, a primer in said casing, a firing pin for igniting said primer, a spindle rotatably mounted on said casing, a clockwork for rotating said spindle, a revolute dome for 10 setting the fuse according to the desired distance of the bursting point, a spring-controlled locking arm for retaining the firing pin in cocked position, and a spring for said arm, said locking arm being mounted on 15 said spindle to rotate in unison therewith and adapted to be axially displaced relatively thereto by the action of said controlling spring for releasing said firing pin, and a safety-device normally arresting said locking arm against displacement until released upon the firing of the projectile, said dome having a projecting portion coöperating with said locking arm during the turning of said spindle and being provided with 20 a recess allowing the locking arm to be axially displaced relatively to said spindle for 25 releasing the firing pin.

9. A mechanical time fuse having a casing, a primer in said casing, a firing pin for 30 igniting said primer, a spindle rotatably mounted on said casing, a clockwork for rotating said spindle, a revolute dome for 35 setting the fuse according to the desired distance of the bursting point, a spring-controlled arm mounted on said spindle to rotate in unison therewith and a controlling spring for said arm tending to axially displace said arm relatively to said spindle, and a safety device normally arresting said 40 arm against displacement until released upon the firing of the projectile, said dome having a projecting portion coöperating with said arm during the turning of said spindle and being provided with a recess 45 allowing the arm to be axially displaced relatively to said spindle, and said arm having an annular collar normally retaining the firing pin in cocked position and adapted to release the firing pin, when said arm 50 has entered said recess.

10. A mechanical time fuse having a casing, a primer in said casing, a firing pin for igniting said primer, a spindle rotatably mounted on said casing, a clockwork having 55 a driving spring for rotating said spindle, a revolute annular setting member inclosing said clockwork for setting the fuse according to the desired distance of the bursting point, a locking member for retaining the firing pin in cocked position, said locking member being mounted on said spindle to rotate in unison therewith and adapted to be displaced relatively thereto for releasing said firing pin, a safety device normally arresting said locking member against displacement until released upon the firing of the projectile; said setting member having a portion coöperating with said locking member during the turning of said spindle and being formed to permit the locking 60 member to be displaced relatively to the spindle for releasing said firing pin, when said spindle has reached a predetermined

device controlled by said driving spring normally arresting said locking member against displacement until released upon the firing of the projectile, said setting member having a portion coöperating with said locking member during the turning of said spindle and being formed to permit the locking member to be displaced relatively to the spindle for releasing said firing pin, when said spindle has reached a predetermined angular position, and means for causing such displacement.

11. A mechanical time fuse having a casing, a primer in said casing, a firing pin for igniting said primer, a spindle rotatably mounted on said casing, a clockwork having 81 a driving spring for rotating said spindle, a revolute dome for setting the fuse according to the desired distance of the bursting point, a spring-controlled locking arm for retaining the firing pin in cocked position, a controlling spring for said arm tending to axially displace it, said locking arm being mounted on said spindle to rotate in unison therewith and adapted to be axially displaced relatively thereto by the action of its 91 controlling spring for releasing said firing pin; a hook-shaped lever mounted on said casing and normally engaging over said locking arm with an inclined surface, thereby arresting said locking arm against turning in unison with said spindle and against displacement relatively thereto until released upon the firing of the projectile by the action of inertia, said dome having a projecting portion coöperating with said locking arm during the turning of said spindle and being provided with a recess allowing the locking arm to be axially displaced relatively to said spindle for releasing the firing pin.

12. A combination time and percussion fuse having a casing, a primer in said casing, a firing pin for igniting said primer, a spindle rotatably mounted on said casing, a clockwork for rotating said spindle, a revolute annular setting member inclosing said clockwork for setting the fuse according to the desired distance of the bursting point, a locking member for retaining the firing pin in cocked position, said locking member being mounted on said spindle to rotate in unison therewith and adapted to be displaced relatively thereto for releasing said firing pin, a safety device normally arresting said locking member against displacement until released upon the firing of the projectile; said setting member having a portion coöperating with said locking member during the turning of said spindle and being formed to permit the locking member to be displaced relatively to the spindle for releasing said firing pin, when said spindle has reached a predetermined

angular position, means for causing such displacement and a stop on said setting member for preventing said spindle from rotating after the release of said safety-
device, when said setting member is set for
percussion action of the fuse.

5 The foregoing specification signed at

Erfurt, Germany, this 16th day of April,
1913.
